(57) **CLAIM**

The ornamental design for a ceiling light fixture as shown.

DESCRIPTION

FIG. 1 is a front right perspective view of a ceiling light fixture installed in a ceiling, showing a first embodiment of the new design;

FIG. 2 is a front left perspective view thereof;

FIG. 3 is a rear right perspective view thereof;

FIG. 4 is a rear left perspective view thereof;

FIG. 5 is a front right perspective view of a ceiling light fixture installed in a ceiling, showing a second embodiment of the new design;

FIG. 6 is a front left perspective view thereof;

FIG. 7 is a rear right perspective view thereof;

FIG. 8 is a rear left perspective view thereof;

FIG. 9 is a left view of a ceiling light fixture, showing the first embodiment without the ceiling installation for clarity of illustration;

FIG. 10 is a right view thereof;

FIG. 11 is a front right perspective view;

FIG. 12 is a front left perspective view;

FIG. 13 is a rear right perspective view thereof;

FIG. 14 is a rear left perspective view thereof;

FIG. 15 is a left view of a ceiling light fixture, showing the second embodiment without the ceiling installation for clarity of illustration;

FIG. 16 is a right view thereof;

FIG. 17 is a front right perspective view;

FIG. 18 is a front left perspective view;

FIG. 19 is a rear right perspective view thereof; and,

FIG. 20 is a rear left perspective view thereof.

The broken lines in the figures show portions of the ceiling light fixture and/or ceiling that form no part of the claimed design.

1 Claim, 18 Drawing Sheets
